UNITED STATES PATENT OFFICE.

ALLEN M. STEEN, OF CRAFTON, PENNSYLVANIA.

SANDING DEVICE.

1,247,592.

Specification of Letters Patent. Patented Nov. 20, 1917.

Application filed June 28, 1916. Serial No. 106,458.

To all whom it may concern:

Be it known that I, ALLEN M. STEEN, a citizen of the United States, residing at Crafton, in the county of Allegheny and State of Pennsylvania, have invented new and useful Improvements in Sanding Devices, of which the following is a specification.

This invention relates to a track-sanding device adapted to be used on cars, locomotives and the like, and one of the objects of the invention is to provide means whereby sand from a sand-box or reservoir may be directed upon the rail, irrespective of whether the vehicle is traveling on a straight track or on a curve.

Heretofore sanding devices have been used in which a discharge tube was rigidly fixed with relation to the vehicle, and the outlet end of the tube was near enough to the rail-tread to work more or less satisfactorily when the vehicle was traveling along a straight track. When however, (as in the case of locomotive sanding devices) the vehicle happened to be traveling around a curve, the outlet end of the sanding tube would in many instances be swung out of line with the rail-tread, and as a result the sand would not be directed upon the rail to prevent the wheels from slipping.

A device constructed in accordance with my invention will not only distribute the sand over the rail-tread in a most efficient manner, but will also effectively perform the desired function when the vehicle is rounding a curve.

In the drawings:

Figure 1 is an end elevational view of a sanding device constructed in accordance with my invention.

Fig. 2 is a plan view of the sanding device the bracket and pipe being shown in sections on the line 2—2 of Fig. 3.

Fig. 3 is a vertical longitudinal sectional view through the sanding device, a rail being shown in side elevation.

Fig. 4 is a cross-sectional view through the distributor, and,

Fig. 5 is a bottom view of the distributor.

Referring now to the drawings by numerals of reference;

10 designates a discharge tube of usual construction which is connected to a sand-box or reservoir in the usual manner. As shown, the tube 10 terminates a short dis-

tance above the tread of the rail 11, and at its lower extremity it is provided with a transverse pin 12 which extends entirely through the walls of the tube 10. The pin 11 is provided with projecting ends 13 and 14 which engage elongated slits 15 and 16 in the split collar 17 which serves as a bracket for the sand distributor 18. By reference to Fig. 3 it will be observed that the distributor or shoe may consist of a hollow casting, having a discharge conduit of variable cross-sectional area the greatest area being at the upper end 19 of the casting and sufficiently extensive to receive the depending end of the tube 10. The opposite or lower end of the conduit is restricted and merges into a transverse elongated discharge slot or nozzle 20, the length of which is preferably somewhat less than the width of the rail-tread; so that the sand will be distributed upon the tread of the rail in an efficient manner.

The collar 17 is provided with two laterally projecting ears 21 and 22 between which is a hinge projection 23 integral with casting 18 and both ears 21 and 22 and the member 23 are provided with alining openings for the reception of the hinge bolt 24 whereby a hinge is provided which is offset with respect to the tube 10 and whereby the casting may have a vertically swinging movement so that the discharge end may be raised and lowered by a linkage system, for example, a link 25 connected at one end to the casting 18 and to a similar casting at its other end. Between the ends of the link 25 is a lift rod 26 which may be operated in any desired manner.

In order to prevent the accidental displacement of the casting 18, due to side thrust, I provide downwardly projecting flanges 27 and 28 which fit the respective sides of the rail-tread, and these flanges are of sufficient depth at the front end of the casting to engage the sides of the rail-tread, but they gradually merge into the wall of the casting 18, as at 29, (best shown in Fig. 5). The object of so constructing the flanges 27 and 28, is to permit the shoe to readily ride over frogs, switch-points and the like when the device is lowered upon the rail for use.

From the foregoing description it will be apparent that the sanding shoe is capable of having both a vertical and laterally swing-

ing movement, because the hinge consisting of the ears 21 and 22 and the member 23 and the bolt 24 permit vertical movement, while the pin 12 in the slots 15 and 16 permit the collar to have sufficient play to permit a laterally swinging movement to be imparted to the casting. For this purpose the link 25 may be connected to castings on the respective tubes 10 above the two rails of the track. When the shoe is lowered upon the rail-tread any liability of its being displaced will be eliminated by the flanges 27 and 28.

For convenience I have shown the pin 12 extending entirely through the tube 10, it being obvious however that trunnions may be cast on the outer walls of the tube if it is so desired.

While I have primarily shown the device as adapted for a locomotive, it is obvious that it may be attached to other appropriate devices if desired.

What I claim and desire to secure by Letters Patent is;

25 1. A sanding device comprising a shoe having a sand receiving and distributing conduit therein, a pipe-engaging collar and a

hinge connected between the collar and the shoe.

2. A sanding device comprising a distributor, depending rail-flange engaging guides on the distributor and means for connecting the distributor to a sand conduit.

3. A sanding device comprising a hollow casting having a sand-pipe-receiving conduit terminating in an elongated sand distributing outlet, guide flanges depending from the casting and a collar hinged to the casting and provided with opposite elongated slots.

4. A sanding device comprising in combination with a sand conduit, a distributor connected to one end of said pipe in a manner to have vertical and lateral angular movements and constructed to engage a rail and follow the contour thereof so as to receive said movements.

In testimony whereof I affix my signature in presence of two witnesses.

ALLEN M. STEEN.
